UNITED STATES PATENT OFFICE.

JOHN W. SMITH, OF WICKENBURG, ARIZONA TERRITORY.

WATER-CIRCULATING APPARATUS FOR INTERNAL-COMBUSTION ENGINES.

No. 905,379.

Specification of Letters Patent.

Patented Dec. 1, 1908.

Application filed March 28, 1907. Serial No. 365,000.

To all whom it may concern:

Be it known that I, JOHN W. SMITH, a citizen of the United States, residing at Wickenburg, in the county of Maricopa and 5 Territory of Arizona, have invented certain new and useful Improvements in Water-Circulating Apparatus for Internal-Combustion Engines; and I do declare the following to be a full, clear, and exact description of the invention, such as will enable others skilled in the art to which it appertains to make and use the same.

This invention relates to improvements in water circulating apparatus for internal 15 combustion engines, air compressors and the like.

The object of the invention is to provide an apparatus of this character adapted to be automatically operated by the engine or 20 compressor to provide for a continuous circulation of water in the jacket of the engine or compressor cylinder.

With the above and other objects in view, the invention consists of certain novel features of construction, combination and arrangement of parts, as will be hereinafter described and claimed.

In the accompanying drawings is shown a side elevation of an engine having applied 30 thereto a water circulating apparatus constructed in accordance with the invention.

Referring more particularly to the drawings, 1 denotes the engine, which may be of any form of internal combustion engine, the 35 same being here shown in upright form. Connected to the jacket 2 of the engine cylinder adjacent to its lower end is a cold-water inlet or supply pipe 3, the opposite end of which is connected to a water tank 4 or other source of supply 4. Connected to the upper end of the water jacket is a discharge pipe 5 at the upper end of which is arranged a T-coupling 6, with one branch of which is connected a continuation 7 of the 40 discharge pipe 5. The opposite end of said pipe 7 is connected to the upper end of the water tank 4, as shown.

To the branch of the coupling 6 opposite to that with which the pipe 7 is connected is 50 secured a reducing coupling 8, with which is connected one end of a small injecting pipe 9. The opposite end of the pipe 9 is connected to a union 10, to which is also connected a short nipple 12. The outer end 55 of the nipple 12 is connected to a curved or arched pipe 13, the opposite or lower end of

which is connected to a T-coupling 14, one branch of which is connected by a nipple 15 to the combustion chamber of the engine. The free or lower branch of the coupling 14 has connected thereto a discharge valve 16, while in the pipe 13 above the coupling 14 is arranged a cut off valve 17.

In the operation of the apparatus the valve 16 is closed and the valve 17 opened 65 immediately after the starting of the engine, so that as a result of the explosions in the cylinder the air will be driven through the pipe 15 into pipe 13 and through the reduced nipples or connecting pipes 12 and 70 9 and into the end of the pipe 7 forcing the water through the same into the tank and drawing the water up through the pipe 5 to produce a vacuum therein, which will cause the water from the jacket to circulate around 75 through the same from the supply pipe 3 and to pass out of the discharge pipes 5 and 7 into the tank, whereby the water is cooled and again enters the lower end of the jacket through the inlet or supply pipe 3. 80

While the air pipe 15 is herein shown and described as being connected directly to the combustion cylinder of the engine, it has been found that sufficient pressure of air to operate the device may be had by connecting 85 said pipe 13 with the exhaust pipe of the engine, thereby utilizing only a portion of the force of air resulting from the explosions within the cylinder.

When the apparatus is not in use or the 90 engine not running the discharge valve 16 at the lower end of the pipe 13 will be opened and the valve 17 closed, thereby preventing any water from being drawn into the cylinder upon the starting of the engine, said valve 16 being closed and the valve 17 opened immediately after the starting 95 of the engine.

For the purpose of illustration the apparatus is shown and described in connection 100 with an upright explosive engine. It will be understood however that the device is equally well adapted for use in connection with air compressors and other forms of engines or motors, having a water jacket, 105 to promote a circulation of water therethrough. The device when used on air compressors is operated by a portion of the compressed air taken from the compressor cylinder.

From the foregoing description, taken in connection with the accompanying draw-

ings, the construction and operation of the invention will be readily understood without requiring a more extended explanation.

Various changes in the form, proportion and the minor details of construction may be resorted to without departing from the principle or sacrificing any of the advantages of the invention, as defined by the appended claims.

10 Having thus described my invention, what I claim as new is:—

1. The combination with an internal combustion engine having the water jacket provided with an inlet and an outlet pipe, of an arched air-conducting pipe connected at one end to the piston chamber of said engine, a cut-off valve in said air pipe, and an injector arranged between and connected with the other end of said air pipe and the outlet pipe of said jacket to assist in drawing the water from the jacket and forcing it out through the discharge pipe.

2. The combination with a combustion engine having a water jacket provided with an inlet and an outlet pipe, of an arched air-conducting pipe adapted to be connected at one end to the combustion chamber of the engine, a cut-off valve arranged in said air pipe, a discharge valve arranged in the end thereof below the connection between said pipe and said combustion chamber, and a

reduced detachable connection between the inner end of said air pipe and the water discharge or outlet pipe of the water jacket to form an injector for the air from said air pipe to said discharge pipe.

3. The combination with an internal combustion engine having a water jacket provided with an inlet and an outlet pipe, of an arched air-conducting pipe adapted to be connected at one end to the combustion chamber of the engine, a cut-off valve arranged in said air pipe, a discharge valve arranged in the end thereof below the connection between said pipe and said combustion chamber, a reduced connection between the opposite end of said air pipe and the water discharge pipe of said jacket, said connection comprising a union, nipples to connect said union with the end of the air pipe and with a T-coupling arranged in said water discharge outlet pipe, and a reducing coupling between the end of one of said nipples and said T-coupling.

In testimony whereof I have hereunto set my hand in presence of two subscribing witnesses.

JOHN W. SMITH.
